US0D1076890S

(12) **United States Design Patent** (10) **Patent No.:** **US D1,076,890 S**
(45) **Date of Patent:** **** May 27, 2025**

(54) **MICROPHONE**

(71) Applicants: **Pixie Dust Technologies, Inc.**, Tokyo (JP); **FrontAct Co., Ltd.**, Tokyo (JP)

(72) Inventor: **Takuma Yamazaki**, Yokohama (JP)

(73) Assignees: **FrontAct Co., Ltd.**, Tokyo (JP); **Pixie Dust Technologies, Inc.**, Tokyo (JP)

(**) Term: **15 Years**

(21) Appl. No.: **35/520,250**

(22) Filed: **Mar. 2, 2023**

(80) **Hague Agreement Data**

Int. Filing Date: **Mar. 2, 2023**

Int. Reg. No.: **DM/228331**

Int. Reg. Date: **Mar. 2, 2023**

Int. Reg. Pub. Date: **Mar. 8, 2024**

(30) **Foreign Application Priority Data**

Sep. 28, 2022 (JP) ..... 2022-020842 D

(51) **LOC (15) Cl.** **14-01**

(52) **U.S. Cl.**

USPC **D14/225**; D14/228

(58) **Field of Classification Search**

USPC D14/225, 228, 149–150, 215–216, 227, D14/242, 218, 211–212, 358; D10/60, D10/81; D21/324; 436/37; 463/46; D28/78, 82; 132/295

CPC . H04W 88/00; H02J 1/00; H04R 1/02; H04R 25/00; H04R 2420/07; A45D 34/04; A45D 40/24

FOREIGN PATENT DOCUMENTS

CN 303265816 * 7/2015

Primary Examiner — Paula Allen Greene

(74) Attorney, Agent, or Firm — The Webb Law Firm

(57) **CLAIM**

The ornamental design for a microphone as shown and described.

DESCRIPTION

1. Microphone

1.1: Front perspective view

1.2: Front view

1.3: Back view

1.4: Top view

1.5: Bottom view

1.6: Right view, the left view is a mirror image

The long and short broken lines depict boundaries of the microphone and the dashed broken lines depict environment in which the design resides; all broken lines form no part of the claimed design.

1 Claim, 6 Drawing Sheets
